UNITED STATES PATENT OFFICE.

KARL F. LILJEGREN, OF DONNA, TEXAS.

WATER GATE.

Application filed August 18, 1924. Serial No. 732,771.

This invention relates to water gates for use in irrigation systems and has for one of its objects the provision of means to enable reciprocable water gates or such as are movable back and forth in the plane thereof to be tightly closed regardless of trash, such as sticks and weeds, which may have accumulated while such gates were in open position.

A further object of the invention is to provide means for effecting water tight seals between the gates and their guides while at the same time rendering it easy to operate the gates.

A further object of the invention is to provide improved lifting devices for such gates.

According to one form of the invention the gate is formed of a metal plate guided for movement preferably in a vertical plane and having a sharpened lower edge to cooperate with a chopping block in the gate frame in cutting trash which may accumulate beneath the gate. The chopping block may be of wood or other suitable material into which the sharp edge of the gate may be pressed or pounded to cut through the trash collected beneath the gate and shut off the water completely. The feature of the sharp lower edge of the gate cutting into the sill is of very great importance in that it assures a close seal at the lower edge of the gate and not a seal by mere contact as is usually the case. The seal thus formed may be called a cutting seal or an embedding seal.

The sealing of the gate at its edges may be effected by heavy duck belting folded longitudinally and pressed or sprung into position in guide grooves in the frame, the edges of the gate being received in the folds of the belting which may be lubricated or waterproofed as required. Preferably some heavy lubricant is supplied between the edges of the gate and the base of the fold in the belting, not only to provide suitable lubrication but also to assist in effecting a water tight seal. Such sealing may also be effected by means of a suitable heavy lubricant without use of the belting.

The gate lifting device may comprise a lever and a bar attached to the gate and extending upwardly at the inner face thereof, the bar having openings into which the end of the lever may be inserted.

Other features and objects will hereinafter appear.

In the drawings:

55

Fig. 1 is a vertical section across the frame of the gate;

Fig. 2 is a vertical section in a plane perpendicular to that of Fig. 1;

Fig. 3 is a horizontal section showing the manner of sealing the gate at its lateral edges; and

Fig. 4 is a view similar to Fig. 3 but illustrating another form of edge seal.

Referring to Figs. 1, 2 and 3 a gate 10, in the form of a metal plate, is guided for vertical movement in grooves 11 in a gate frame 12 of suitable material such as concrete. The edges of the gate do not engage the frame directly but enter the folds in longitudinally folded strips 13 of heavy duck belting forced into said grooves 11. For waterproofing use is made of a heavy grease seal 14 in the fold of each of the strips of belting. This grease also serves as a lubricant to make the gate move more easily.

Gates heretofore in use were frequently prevented from effective closing at the bottom by means of accumulations of trash beneath the gates. The gate 10 is, however, provided with a beveled lower edge, so sharp that in connection with a wooden chopping block or sill 15 at the bottom of the frame, trash accumulated beneath the gate may be cut through by pressing or pounding the gate down against the chopping block. In this manner a tight closing at the bottom of the gate will be obtained. As indicated in Fig. 1, the chopping block or sill 15 may be made up of a number of blocks or sections:

90

For controlling the position of the gate 10, provision is made by a strip or bar 16 having one end secured by suitable means, such as rivets, to the upper edge of the gate and extending upwardly for a short distance and then rearwardly and downwardly parallel to the gate. The downward extension of the bar 16 has a reverse curve at its lower end to hold the bar away from the gate, and said lower end is secured to the gate 10 by suitable means such as rivets. Extending through the bend at the upper end of the bar 16 and secured to the forward of the two parallel portions thereof is a cross bar or handle 17 for use in lifting the gate when it works comparatively easily as in the case of a small gate.

For use when additional power is required

to lift the gate 10 provision is made of a channel bar 18 extending across the gate opening and anchored to the frame, and a vertical fulcrum standard 19 attached to the bar 18 and having openings 20 through which a lever 21 may be thrust to project into any one of a series of openings 22 in the rear portion of the bar 16. Projecting forwardly from the lower end of the standard 19 is a flange 23 in the path of a stop 24 projecting from the lower end of the bar 16, the flange 23 and stop 24 serving to limit the upward movement of the gate. When the gate has been lifted, as, for example, by the lever 21, further lifting may be effected by holding the gate by pressing a pin or lever through one of the openings 22 and resting it on any convenient object as the standard 19 or the bar 18, and changing the position of the lever 21 by passing it through another opening 22 to take a fresh start.

According to another form of the invention shown in Fig. 4, the belting in the grooves is omitted and the closed end of each groove is provided with an offset portion to hold a heavy water proofing grease seal 25 from which portions of the grease work into the spaces between the gate 10 and walls of the slots. This forms an effective seal and permits easy shifting of the gate 10.

Although, according to the preferred embodiment of the invention, the cutting of trash is effected by a gate in the form of a metal plate with a sharpened lower edge and a sill or block of wood, it should be understood that other arrangements may be made without departing from the spirit of the invention. For example, it is immaterial whether any portion of the gate except its lower edge is of metal or whether the sill 15 is of wood or of other material which is softer than the sharp edge of the gate.

Variations may be resorted to within the scope of the invention and portions of the improvements may be used without others.

Having thus described my invention, I claim:

1. The combination with an upwardly and downwardly movable water gate, of a frame 50 having side walls by which the gate is guided in such movement and a sill to coact with the lower edge of said gate, one of such coacting parts having a sharp knife-like coacting part and the other of such parts being 55 of softer material than the knife-like part and serving as a chopping block against which trash may be cut and into which the sharp knife-like part may be forced to effect a tight embedding closure at the bottom of 60 the gate.

2. The combination with a reciprocable water gate having a sharp lower edge, of a frame having at its sides means for guiding the gate and at the bottom thereof a 65 chopping block, of softer material than the sharp edge of the gate, against which trash may be cut and into which said sharp edge may be forced to effect a tight embedding closure at the bottom of the gate. 70

3. The combination with a reciprocable water gate, of a frame having at its bottom a sill with which the lower edge of the gate coacts to effect a close seal and side walls with grooves for guiding the edges of the 75 gate, and longitudinally folded strips of heavy flexible material forced into said grooves and receiving in the folds thereof the edges of said gate.

4. The combination with a reciprocable 80 water gate, of a frame having at its bottom a sill with which the lower edge of the gate coacts to effect a close seal and side walls with grooves for guiding the edges of the gate, longitudinally folded strips of heavy 85 flexible material forced into said grooves and receiving in the folds thereof the edges of said gate and heavy lubricant in the folds of said strips to assist in sealing the side edges of the gate. 90

In witness whereof I affix my signature.
KARL F. LILJEGREN.
